UNITED STATES PATENT OFFICE.

JOHN B. CROFOOT, OF CHICAGO, ILLINOIS.

STAPLING-MACHINE.

1,224,075.

Specification of Letters Patent. Patented Apr. 24, 1917.

Application filed October 28, 1915. Serial No. 53,469.

To all whom it may concern:

Be it known that I, JOHN B. CROFOOT, a citizen of the United States, residing at Chicago, in the county of Cook and State of Illinois, have invented certain new and useful Improvements in Stapling-Machines, and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in tacking or stapling machines and the object in view is to generally improve upon and render more efficient this type of apparatus.

The present invention consists essentially, first in the provision of a novel means for advancing the staple strip to the proper position to have a fastener severed and driven into an object. Another and an essential feature of the invention consists in the provision of extension means upon the plunger cap for acting as an automatic stop and serving as a means to protect the spring which acts as a plunger.

Another feature of the invention consists in the provision of a T-shaped knife so arranged that, when removed, it will allow the staple strip to drop from the casing.

The invention consists further in various details of construction and arrangements of parts whereby the different features of the invention may be readily assembled and disassembled, when desired, for repairs, etc.

My invention is illustrated in the accompanying drawings, in which:

Figure 1 is a central vertical sectional view through a tacking or stapling machine embodying the features of my invention.

Fig. 2 is a section on line 3—3 of Fig. 1.

Fig. 3 is a perspective view of the cutting knife.

Reference now being had to the details of the drawings by numeral, 1 designates the casing of the apparatus which may be of any suitable size or shape and which is provided with a handle 2, and 3 is a vertical way formed near one end of the casing and in which the plunger 4 is adapted to have a vertical longitudinal movement. Said plunger has a notch 5 in one side and has a cap

6 which is hollow to receive the upper contracted end 7 of the plunger to which it is held by means of a pin 8. A coiled spring 9 is mounted about said plunger and bears against the under surface of the head 6 and extends about the hollow shank portion of said head and its lower end rests upon the upper edge of the casing about the way in which the plunger is mounted, said shank portion of the cap being adapted to guide the spring and coöperating with the casing to limit the movement of the plunger in one direction, and thereby protect the spring from injury.

The forward end of the bar 13 is also provided with a shoulder 13^a, adapted to co-operate with the shoulder 14^a formed at the base of the notch 5 of the plunger 4 for limiting the upward movement of the plunger 4.

Mounted within the slotted bottom of the casing is a block 11 having a cutter edge and which block is inverted T-shape in cross section, as shown, said cutter block being held in place by fastening means passed through registering apertures 12 in the walls of the slot and in said cutter block. It will be understood that said block also serves the purpose of a guide for the staple strip.

A longitudinally movable bar 13 is mounted in a horizontal recess in the casing and is held to its limit in one direction by means of a coiled spring 14 bearing intermediate the bottom of the recess in which the bar is mounted and the inner end of the latter. Said bar 13, preferably of a suitable metal and case hardened, is recessed upon its under surface and carries a pivotal pin 15 upon which the upper end of a pawl 16 is pivoted. The free end of said pawl is forked and is adapted to engage and feed forward a staple strip 17. The forward end of the bar 13 is beveled as at 13^a and is adapted to engage a beveled edge 3^a formed in the edge of the plunger when the latter is in its normal elevated position, the bar 13 at its forward end having a shoulder which fits over the lower end of the notch therein. A spring 18 bears yieldingly against the pawl and is adapted to hold the same yieldingly against the staple strip which rests and moves upon the upper edge of the cutter block 11.

In order to prevent a reverse movement to the staple strip after having been fed forward, a second pawl, designated by numeral 18^a, is pivotally mounted upon

a pin 19 and a spring 20 serves to hold the pawl 18', the free end of which is notched or forked, in engagement with the staple strip at a location adjacent to the previous 5 staple which has been severed therefrom.

In operation, the staple strip is adjusted over the cutter block in the manner shown in the vertical central sectional view of the drawings and, when the plunger is driven downward, the beveled edge with the notch 10 therein, coming against the beveled edge of the bar, will cause the latter to be forced back against the tension of the spring 14. The pawl 16 being pivoted to said bar will 15 move therewith and will be thrown out of engagement with the staple strip. When the lower end of the plunger comes in contact with the projecting portion of the staple strip, a staple will be severed by the 20 shearing action of the lower end of said plunger with the cutter block and continued downward movement of the plunger will drive the staple into the object beneath. The second pawl 18' will hold the staple 25 strip from rearward movement during the operation of the machine. When pressure is released from the plunger, the spring 9 bearing yieldingly thereon will return the plunger to its farthest upper limit and, 30 when the notched portion thereof comes opposite the beveled end of the bar 13, the spring 14 acting against the inner end of the latter will throw the bar 13 out into the

notch to its normal position and in the forward movement of the bar 13 the pawl 16 35 will be moved therewith and feed the staple member forward so that another staple will be in position to be severed and driven upon the next downward thrust of the plunger.

By the provision of a tacking or stapling 40 machine made in accordance with my invention, it will be noted that a movement is given the staple strip through the means described and the cutter block is of such a construction that, when being removed, 45 the staple strip will readily fall from the casing and, by the provision of the cap as shown and described, means is provided for protecting and guiding the spring.

What I claim to be new is:—

In a stapling machine, a body, a reciprocating staple setting plunger, a spring for moving the plunger upwardly, a bar operating at right angles to the reciprocating plunger, means carried by the bar for feeding the staples forward, and means carried by the plunger and co-operating with the bar for restricting the vertical movement of the plunger against the tension of the spring.

In testimony whereof I hereunto affix my 60 signature in presence of two witnesses.

JOHN B. CROFOOT.
